COMBINED CAN PUNCH OPENER AND CLOSURE

Roger R. Shumway, Glendale, Ariz., and Donald C. Bortel, 6301 W. Oregon, Glendale, Ariz. 85301; said Shumway assignor to said Bortel

Filed Oct. 21, 1974, Ser. No. 516,391

Term of patent 14 years

Int. Cl. D7—99

U.S. Cl. D8—34

FIG. 1

FIG. 2

FIG. 3

FIG. 4

FIG. 5

FIG. 1 is a top plan view of a combined can punch opener and closure showing our new design;

FIG. 2 is a bottom plan view thereof;

FIG. 3 is a top perspective view thereof;

FIG. 4 is a bottom perspective view thereof; and
FIG. 5 is an enlarged cross-sectional view taken along lines 5—5 of FIG. 3.

We claim:

The ornamental design for a combined can punch opener and closure, as shown.
